UNITED STATES PATENT OFFICE.

CYRUS C. SHIGLEY, OF GRAND RAPIDS, MICHIGAN.

CHECK OR COIN CONTROL APPARATUS.

1,310,549.

Specification of Letters Patent.

Patented July 22, 1919.

Original application filed November 10, 1916, Serial No. 130,626. Divided and this application filed November 26, 1917. Serial No. 203,993.

To all whom it may concern:

Be it known that I, CYRUS C. SHIGLEY, a citizen of the United States, residing at Grand Rapids, Michigan, have invented certain new and useful Improvements in Check or Coin Control Apparatus, of which the following is a specification.

This invention relates to improvements in check or coin controlled apparatus. This application is a division of application Serial No. 130,626, filed November 10, 1916.

The objects of this invention are:

First, to provide check controlled means by which a motor is automatically started by the insertion of a check, and stopped after the apparatus driven by the motor performs a certain cycle of operations.

Second, to provide an apparatus of the character described so constructed that a plurality of checks may be inserted in the check chute at one time, the checks being passed through the control apparatus one at a time, so that the driven apparatus performs a complete cycle for each of the checks.

Further objects, and objects relating to details of construction and operation, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Figure I is a detail front elevation of my improved check controlled apparatus shown in connection with certain portions of the phonograph described and claimed in my application above referred to.

Fig. II is an enlarged detail front elevation with the cover plate of the check chute removed.

Fig. III is a transverse section of Fig. II.

Fig. IV is a rear elevation of the parts shown in Figs. II and III.

In the drawings similar numerals of reference refer to similar parts throughout the several views.

For the purpose of making the operation of my improved check controlled apparatus clear, I have illustrated it in connection with the phonograph described and claimed

in my co-pending application above referred to, only those portions of the phonograph structure being illustrated which are deemed necessary for a clear understanding of my present invention.

Referring to the drawing, the reference character 1 indicates a motor which is connected with the drive wheel 2 by the belt 3. This drive wheel 2 has frictional engagement with the mandrel 3' mounted upon the shaft 4, whereby the shaft is rotated. Secured to the front end of the shaft 4 is a friction drive wheel 5 that engages with the periphery of the control wheel 6. The mandrel and friction drive wheel 5 are mounted upon a carriage 7 which, at certain times during the operation of the phonograph, is moved so as to bring the friction drive wheel 5 into driving relation with the control wheel 6, thereby rotating the latter and controlling certain operations of the phonograph and likewise of the check controlled apparatus about to be described.

This apparatus comprises a supporting block 8 of insulating material having a check chute formed in the front face thereof. This chute is preferably provided with a glass face plate 10, which permits the operator to see the check as it descends into actuating position.

Situated intermediate the ends of the chute 9 is a pair of contact members 11 and 12 respectively. The first contact member is rigidly secured by means of the binding post 13. The contact member 12 is pivotally mounted to oscillate upon the front end of the binding post 14.

A pin 15 secured in the block 8 projects through an opening 16, having a diameter larger than that of the pin, and thereby limits the movement in either direction of the contact member 12. The contact member 11 has vertically spaced check supporting projections or contact points 17 and 18, and the contact member 12 is provided with similar check supporting points 19 and 20.

Contact member 12 is actuated from the control wheel. To accomplish this I provide a rock shaft 21 having an arm 22 thereon connected by the spring 23 to the contact member 12, the spring being provided with a pair of arms 24 and 25, the arm 24 being connected to the insulating block 26 and the arm 25 to the contact member. This spring and its arms are so disposed that they swing

past a dead center as the arm 22 is swung, thereby serving to hold the contact member 12 yieldingly in either position, and actuating it with a snap-like action. A stop 27 is provided for the arm 22.

The rock shaft 21 is actuated from the control wheel, the rock shaft being provided with an arm 28 connected to the wrist pin 29 on the control wheel by the link 30, so that the check contacts are controlled by the movement of the control wheel.

The operation of the structure thus far described will now be explained: When the check C, which is ordinarily a coin, drops 15 into the check chute 9, it is arrested by the check supporting projections 17 and 19, the contact member 12 being in the position shown in full lines in Fig. II. The circuit to the motor is thereby closed, the current 20 flowing through the check C from one contact member to the other, and the motor starts, thereby rotating the drive wheel 2. This, as is described in detail in my said application, drives the mandrel and also the 25 carriage to advance and also retract the same. On the return of the carriage the friction wheel 5 engages and rotates the control wheel.

The control wheel rotates in the direction of the arrow in Fig. I. Owing to the downward movement of the wrist pin 29, the arm 22 is gradually urged upward through the rock shaft 21, arm 28 and link 30, thereby placing the spring 23 under tension until its dead center is reached, when the contact member 12 is suddenly snapped into the position indicated in dotted outline in Fig. II. This permits the check C to drop to the position shown in dotted outline in Fig. II, in which position it is arrested by the check supporting projections 18 and 20. Further movement of the control wheel carries the wrist pin 29 from its lowermost position to the position indicated 45 in Fig. I. The arm 22 is gradually moved downward again, placing the spring 23 under tension until the dead center is passed, when the contact member 12 is suddenly snapped to the position shown in full lines 50 in Fig. II, thereby discharging the check downwardly through the chute. In case there are a plurality of checks in the chute, the one next to the lowermost check, or the one which has just been discharged, will be 55 arrested by the check supporting projections 17 and 19 and the operation of the driven apparatus will be repeated. This mode of operation will continue as long as there are checks above the contact members 60 11 and 12.

To shorten the length of time during which the circuit is broken while the check C is dropping from the position shown in full lines to that shown in dotted lines, I 65 provide the binding post 31 with which the

contact member 12 contacts when in the position indicated in dotted outline in Fig. II. This binding post is connected by a short circuiting wire 32 with the binding post 13 of the contact member 11. By this means as soon as contact member 12 makes contact with binding post 31, the circuit between binding posts 13 and 14 is completed. Inasmuch as the contact between the member 12 and the binding post 31 is made before the check C reaches the position indicated in dotted outline, it will be seen that the time during which the circuit is broken is shortened by the use of this short circuiting wire. 70 75 80

While I have illustrated and described my invention in connection with a phonograph structure, it will be obvious that it can be used in connection with any motor driven apparatus which it is desired to start 85 by the insertion of a check or coin and which is to be stopped after a definite cycle of operations. My invention is, therefore, not to be limited except by the scope of the following claims. 90

Having thus described my invention, what I claim as new and desire to secure by Letters Patent is:

1. In a structure of the class described, the combination with a check chute, a contact member mounted at each side of said chute to engage the edges of checks passing therethrough, one of said members being pivoted, said contact members each being provided with spaced check supporting projections, means for limiting the movement of said pivoted member, a rock shaft provided with an arm, and a spring comprising a pair of arms, one of which is connected to said pivoted contact member and the other to said rock shaft so that on the swinging of the arm the spring is placed under tension until its dead center is reached, thereby securing a snap action for said contact member. 95 100 105 110

2. In a structure of the class described, the combination with a check chute, of a pivoted contact member adapted to support a check in two positions, an actuating rock shaft, an arm on said rock shaft, a spring 115 comprising a pair of arms, one of which is connected to said pivoted contact member and the other to said rock shaft so that on the swinging of the arm the spring is placed under tension until its dead center is reached 120 thereby securing a snap action for said contact member, a control wheel provided with a wrist pin, and an arm on said rock shaft connected to said wrist pin by a link whereby said rock shaft is actuated as said control wheel is rotated to swing the contact member to its second and return it to its initial position on each revolution of the control wheel. 125

3. In a structure of the class described, 130

the combination with a check chute, of a pivoted contact member adapted to support a check in two positions, an actuating rock shaft, an arm on said rock shaft, a spring 5 comprising a pair of arms, one of which is connected to said pivoted contact member and the other to said rock shaft so that on the swinging of the arm the spring is placed under tension until its dead center is reached 10 thereby securing a snap action for said con-

tact member, and means for actuating said rock shaft.

In witness whereof, I have hereunto set my hand and seal in the presence of two witnesses.
